PRESS WITH COMPOUND RAM

Howard F. MacMillin, Mount Gilead, Ohio, assignor to The Hydraulic Press Corporation, Inc., Wilmington, Del., a corporation of Delaware

Application April 22, 1936, Serial No. 75,753

2 Claims. (Cl. 60—97)

This invention relates to presses, and in particular, to a hydraulic press having a compound main ram.

One object of this invention is to provide a hydraulic press with a compound main ram, one portion of which is adapted to impart a relatively low pressing effect to the platen and the other portion a relatively high pressing effect thereto.

Another object is to provide such a press with a compound main ram, wherein one portion is adapted to impart a relatively low pressing effect to the platen and the other portion a relatively high pressing effect thereto, the two portions being adapted to be utilized either separately or simultaneously.

Another object is to provide a hydraulic press having a compound main ram with a plurality of portions to which the operating fluid may be selectively admitted, thereby providing a pair of piston head areas adapted to give different speeds and pressing force to the platen, one area being capable of imparting a relatively high speed to the platen with a relatively low pressing force, and the other area being capable of imparting a slower speed to the platen with a higher pressing force.

Another object is to provide a hydraulic press circuit having a press with a compound main ram and a valve arranged to deliver fluid to one portion of the ram during one part of the stroke, and to be shifted to deliver fluid to another portion of the ram during another part of the stroke, this valve being preferably shifted by the motion of the platen.

Another object is to provide a hydraulic press circuit having a press with a compound main ram, and a distributing valve therefor which delivers fluid to the inner area of the ram during the initial part of the pressing stroke, this valve being shifted, as by the platen, to deliver the pressure fluid not only to the inner area but also to an additional outer area so as to complete the pressing operation, with the exertion of a higher pressing force. In this manner the actual working stroke is carried out in two stages, the first stage being accomplished at a relatively higher speed and medium pressure, and the second stage at a slower speed but at full pressure.

In the drawings:

Figure 1 is an elevation, partly in section, of a hydraulic press with a compound main ram and an actuating circuit, according to this invention.

Figure 2 is a central vertical section through

the distributing valve used in connection with the circuit of Figure 1.

Figure 3 is a view, partly in section, showing the arrangement for actuating the valve rod by means of a platen arm.

Figure 4 is a view similar to a portion of Figure 1, but modified slightly to provide a by-pass line and by-pass valve around the distributing valve.

General arrangement

Referring to the drawings in detail, Figure 1 shows a press having side frame members 10, a bed 11 and a top member 12, these being secured to the side members or strain rods 10 by the nuts 13. The bed 11 is provided with an upper surface 14, upon which suitable dies or holders for work-pieces may be placed. The upper frame member 12 is adapted to serve as the cylinder for the main ram, and for this purpose it is provided with a cylinder bore 15, within which is mounted a tubular main ram 16 attached at its lower end to a platen 17, having guide plates 18 adapted to engage the frame side members 10 for guidance during the motion of the platen downwardly toward the bed 11. The platen 17 is provided with lateral extensions 19, to which are attached the threaded upper ends of push-back plungers 20, as by the nuts 21. The push-back plungers 20 operate in push-back cylinders 22 having cylinder bores 23 with glands 24 and packings 25 surrounding the plungers 20 to prevent leakage. The hydraulic connections of these push-back cylinders 22 will be subsequently described.

The main ram 16 is provided with a hollow bore 26 adapted to receive a tubular member 27, having a fluid-tight engagement therewith, as by the piston rings 28 at the bottom thereof. The tubular member 27 is mounted in a bore 29 at the upper end of the frame top member 12, and is provided with a surge valve 30 opening into a surge tank 31 adapted to contain the operating fluid for the pump. Above the upper end of the cylinder bore 15 is an enlarged portion 32, forming an annular chamber 33 surrounding the tubular portion 27.

Mounted in bores 34 above these annular chambers 33 are surge valves 35, similar to the surge valve 30 previously mentioned. The surge valves 30 and 35 may be of any suitable and conventional type, and their details form no part 50 of the present invention. The particular surge valve shown is disclosed in detail in the patent to Walter Ernst, No. 1,892,568, issued December 27, 1932. The surge valves 30 and 35 operate, as will subsequently appear, to permit the main ram 55

16 to descend under the influence of gravity and to draw fluid freely into the main cylinder bore 15 and the inner bore 36, through the surge valves 39 and 35, but when the power is applied to force 5 pressure fluid into this space the surge valves 30 and 35 are automatically closed, causing the remainder of the stroke to take place under pressure. This arrangement serves to permit a more rapid descent of the platen than would be possible 10 if the platen were actuated entirely by fluid pressure. Upon the return stroke of the press the surge valves 30 and 35 open to permit fluid to be discharged into the surge tank 31 in a reverse manner. The tubular member 27 is provided with 15 an inner bore 36, forming a conduit for conducting fluid from the surge valve 30 to the inner bore 26 of the main ram 16, and vice versa. The space between the main ram 16 and the main cylinder bore 15 is closed by a packing 37, adapted 20 to be compressed by a gland 38 therebeneath.

Mounted on one side of the press top member 12 is a distributing valve 40, which serves in cooperation with the pump 39 as a shift-over valve to direct fluid initially to the inner portion 25 of the main ram 16, and finally to the outer portion as well. The main ram 16 is provided with an outer annular piston portion 41 and an inner end wall 42, which receive the thrust of the pressure fluid delivered by the distributing valve 30 40. The details of the distributing valve 40 will be subsequently described.

Hydraulic circuit

The pump 39 is preferably of the reversible 35 variable delivery type, and has a control hand lever 43 arranged to operate the control valve assembly 44 for the servo-motor 45 of the pump 39. For this purpose the control valve assembly 44 is connected by the lines 44a and 44b to the servo-motor 45, and by the line 44c to the forward delivery or pressing side of the pump 39. The servo-motor 45 contains a piston (not shown) 40 adapted to move the shift-ring of the pump 39 to vary and reverse the delivery thereof. Fluid is supplied to the control valve through the lines 45 46 and 47 leading to the pressure and suction sides, respectively, of the low pressure pump 48, the line 46 being likewise connected to the line 61 leading to the surge tank 31. A pressure relief 50 valve 58 by-passes the discharge of the pump 39 into the lines 47 and 61 when the valve 44 closes off the line 46. The servo-motor 45 is also operated automatically by fluid reaching it by the line 45a from the push-back side of the pump 39. The details of the servo-motor form no part 55 of the present invention, and are disclosed in the patent to Walter Ernst, No. 1,861,116, issued May 31, 1932.

The pump 39 on its forward delivery side is 60 connected by the line 64 to a make-up valve 49. This valve 49 is likewise of a conventional type, whose details form no part of the present invention, and contains chambers 50, 51 and 52 interconnected with one another by bores 53 and 54, 65 within which reciprocates the valve member 55 having heads 56 and a fluted body portion 57. The purpose of the make-up valve 49 is to provide for the intake of any necessary amount of fluid upon one side of the press required over 70 that discharged from the other side of the press. It supplies fluid to make up for any difference in volume between the various cylinders, such as between the main cylinder 15 and the push-back cylinders 22.

75 The right-hand end chamber 50 of the make-

up valve 49 is connected by the line 59 to the port 60, opening into the bore 36 of the tubular member 27 and continuing beyond this to the distributing valve 40. The middle chamber 51 is connected by the line 61 to the surge tank 31. 5 The left-hand end chamber 52 is connected by the line 62 to the push-back line 63, leading from the push-back connection 64 of the pump 39 to the push-back cylinders 22. Beyond the left-hand push-back cylinder 22 the line 63 continues 10 in the line 65, leading in triple branch lines 66, 67 and 68 to the actuating chambers of the surge valves 30 and 35. The line 65 is also provided with branches 69 and 70, leading to the distributing valve 40. From the latter the remaining line 15 71 leads to the annular chamber 33 above the main cylinder bore 15. The distributing valve 40 is provided with a valve rod 72, the lower end of which is threaded, as at 73, (Figure 3) to support a nut 74 upon which rests a coil spring 75, 20 surmounted by a tubular cap 76 having a bore 77 through which the valve rod 72 passes. The platen 17 is provided with a valve-actuating arm 78 having a bore 79, through which the valve rod 72 likewise passes.

From Figures 1 and 3 it will be seen that when the platen 17 and the valve-actuating arm 78 descend the latter will eventually engage the tubular cap 76, compressing the spring 75 and forcing the valve rod 72 downwardly to shift 30 the valve member in the distributing valve 40. The position of the tubular cap 76 relatively to the platen arm 78 may be adjusted by rotating the nut 74 so as to change the position at which the platen arm 78 engages the cap 76. 35

Distributing valve

The distributing valve 40 is provided with a casing 80 having a valve bore 81, with upper and lower annular chambers 82 and 83 leading to 40 ports 84 and 85, respectively. The port 84 is connected to the line 59. The port 85, which for convenience of showing is illustrated as diametrically opposite the port 84 instead of ninety degrees away from it, as in Figure 1, is connected 45 to the line 71. The lower and upper portions of the bore 81 are provided with ports 86 and 87, which communicate with the branch lines 69 and 70, respectively, connected to the push-back line 65. Reciprocable within the valve bore 81 50 is a valve member 90 having spaced heads 91 and 92 thereon. The valve member 90 passes through a washer 93, a packing 94 and a gland 95, arranged to compress the packing 94 by 55 tightening the set screws 96.

A spacing element 97 is arranged in the lower part of the bore 81, whereas a tubular element 98 at the upper end of the bore 81 serves to receive the enlargement 99 above the valve head 91. The upper end of the valve member 90 is threaded, as at 100, and is provided with a nut 101 operating against a washer 102 to compress a coil spring 103, the opposite end of which is anchored against the annular element 104 mounted 65 on the gland 105 at the upper end of the distributing valve 40. The gland 105 is similar in construction and operation to the lower gland 95, and is provided with a packing 106 adapted to be compressed by an annular plug 107, threaded 70 into the threaded counterbore 108 of the gland 105, the latter being attached to the casing 80 by means of the set screws 109. A tubular cap 110 serves to protect the upper end of the valve member 90 and render it accessible in order to 75

vary the tension of the spring 103 by adjusting the nut 101.

Operation

The press and circuit shown in Figure 1 may be operated in two different ways, depending upon the nature of the work and the desire of the operator. If it is desired to use only the inner ram of the press, such as for deep drawing work where a maximum ram speed is essential on account of the long stroke under pressure, the cap 76 is lowered by turning the nut 14 upon the valve rod 72 so that it will not be engaged by the platen arm 78 during the downward descent of the platen 17. When the pump 39 is started, therefore, the fluid passes through the pressing connection 64 into the end chamber 50 of the make-up valve 49, and shifts the valve into the position shown in Figure 1. The pressure fluid continues upwardly through the line 59 and the port 60, into the bore 36 within the fixed tubular member 27, whence it enters the hollow bore 26 within the main ram 16. The latter has a small diameter end wall 42 and, assisted by its weight, descends at a relatively high speed, due to the comparatively small volume of the bore 26, which is required to be filled by the fluid.

Meanwhile, the surge valves 30 and 35 have opened as a result of the suction produced by the descent of the main ram 16, permitting fluid to be drawn into the bores 36 and 33, respectively, and thence into the hollow bore 26 of the main ram 16, thereby enabling the main ram 16 to descend more rapidly than would otherwise occur with the action of the pump 39 alone. When the platen 17 engages the work-piece and encounters resistance, the building up of pressure within the inner bore 36 causes the surge valve 30 to close, thereby cutting off communication with the surge tank 31. The pressure within the bore 36 continues to act against the end wall 42 of the hollow bore 26 within the main ram 16 until this pressure exceeds the pressure setting of the servo-motor in the servo-cylinder 45, whereupon this servo-motor will operate the shift-ring of the pump and shift it toward its neutral position, thus cutting down the flow of the pump 39.

Meanwhile, the fluid discharged from the push-back cylinders 22, by reason of the entry of the push-back plungers 20, passes along the line 63 to the push-back connection 64 of the pump 39. Any excess fluid required by the pump 39 for filling the main chamber of the press is supplied by the make-up valve 49. The latter permits fluid to be drawn by the pump 39 from the surge tank 31, through the line 61, the middle chamber 51 of the make-up valve 49, the fluted portions 57 of the valve member 55, the left-hand end chamber 52 and the branch line 62 leading to the pull-back line 63.

When the pump 39 is reversed, to cause the press to execute a return stroke, the push-back connection 63 becomes the pressure connection and the pressing connection 64 becomes the suction connection. Accordingly, the pump 39 delivers pressure fluid to the push-back cylinders 22 by way of the push-back line 63, causing them to move the push-back plungers 20 and the platen 17 upwardly. Pressure fluid passes along the branch line 62 and acts against the valve head 56 in the end chamber 52, shifting the valve to the opposite position from that shown in Figure 1. In the position thus attained by the valve member 55 of the make-up valve 49, fluid passes

between the pressing connection 64, which is now the suction connection, and the surge tank 31 by way of the line 61, the middle chamber 51 of the make-up valve 49, the fluted portions 57 of the valve member 55, the end chamber 50 and the line 64.

The fluid displaced by the upward motion of the main ram 16 passes from the bore 36 of the tubular member 27, through the port 60 and along the line 59 to the right-hand end chamber 50 of the make-up valve 49. If the quantity of this fluid is in excess of that required by the pump 39, the excess fluid passes into the middle chamber 51 and up the line 61, into the surge tank 31. The platen continues its upward motion until its motion is halted by the stopping of the pump 39, or by the automatic action of the servo-motor within the servo-cylinder 45 in shifting the shift-ring of the pump to neutral position.

If now it is desired to use the entire ram area and employ the maximum pressure of the press, the outer annular portion 41 of the main ram 61 must be used in addition to the end wall 42. This employment of the entire area of the ram 16 sacrifices a certain amount of speed, but produces a greater pressing power, such as is desirable for short stroke work, for example, coining and embossing. For this kind of operation the cap 76 is moved upwardly along the valve rod 72 by turning the nut 14 until it is engaged at the proper point by the platen arm 18. The pump 39 is then started and the pressure fluid passing through the line 59 and the port 60 enters and fills the inner bores 26 and 36, assisted by the surge valve 30 as before. The main ram 16 and the platen 17 move downwardly, assisted by their own weight, in the manner previously described, the fluid being similarly displaced from the push-back cylinders 22.

When the platen 17 is moved downwardly to such an extent that the platen arm 78 engages the cap 76, compresses the spring 75 therein and shifts the valve rod 72 and the valve member 90 of the distributing valve 40, the latter shifts so that the heads 91 and 92 (Figure 2) move downwardly. This action opens communication between the valve chambers 82 and 83 and permits the pressure fluid to continue beyond the port 60, along the line 59 to the distributing valve 40. This fluid passes through the port 84, the valve chamber 82, the valve chamber 83, the port 85 (Figure 2) and the line 71 into the annular chamber 33, where it acts upon the annular outer piston portion 41 of the main ram 16. The pressure upon the outer piston portion 41, added to that upon the inner end wall 42, increases the pressing effort exerted upon the platen 17 and further compresses the work-piece. This compression continues until the critical pressure is reached, at which the servo-motor within the servo-cylinder 45 of the pump 39 becomes operative to shift the pump to its neutral position.

When the pump is reversed the pressure fluid flows, as before, through the line 63 into the push-back cylinders 22, raising the platen 17 and the main ram 16 by the action of the push-back plungers 20. This action causes the platen arm 78 to rise and release the cap 76 and the valve rod 72. The coil spring 103 within the distributing valve 40 then shifts the valve member 90 and its heads 91 and 92 upwardly into the normally closed position thereof. This action, however, is counteracted by the flow of fluid along the line 65, from the line 63 into the branch lines 69 and 70, where the pressure from the

push-back line 63 acts upon the unequal areas on the opposite sides of the valve member heads 91 and 92, thereby overcoming the upward urge of the spring 103 and holding the valve member 90 in its downward or open position.

This keeping of the distributing valve 40 open permits the fluid displaced from the annular chamber 33 to escape along the line 71, through the distributing valve 40 to the line 59, which is now the suction line of the pump 39. The surge valves 30 and 35 also open upon the release of pressure in their respective chambers, thereby permitting a portion of the fluid to escape directly into the surge tank 31.

In the second mode of operation of the press, employing both portions 42 and 41 of the main ram 16, the surge valves 30 and 35 operate to permit the entrance of fluid from the surge tank 31 during the early portion of the descent of the main ram 16, in the manner previously described under the first mode of operation, using the central portion 42 of the main ram 16 alone. In the second mode of operation the working stroke will be thus carried out in two stages. The first stage takes place at a relatively higher speed, but applies a medium pressure, and the second stage occurs at a slower speed, but applies a higher pressure. This arrangement not only provides a press which is capable of doing the work of two different kinds of presses most economically, but also increases the speed of action of a high pressure press.

It will be apparent that an additional manual valve 111 (Figure 4) may be placed in the bypass line 112 interconnecting the lines 71 and 59 so as to by-pass the flow of the pump 39 around the distributing valve 40 and permit the outer and inner portions of the main ram 16 to be used from the start of the downward motion thereof, instead of waiting for the distributing valve 40 to be operated by the action of the platen arm 78.

It will also be apparent that the present invention is decidedly superior to and different from the ordinary arrangement of a main ram provided with booster rams for rapidly traversing the main ram to the work. In order to perform the traverse quickly, these boosters must necessarily be small and consequently incapable of doing any effective work. In contrast to this, in the present invention the main ram itself is divided into two major portions, each great enough in area to do useful work, and both completely equipped with surge valve systems for both prefilling and exhausting their respective cylinder chambers during the rapid traverse and rapid return movements. It will be understood, moreover, that in place of the gravity descent or rapid traverse of the platen, booster rams may also be provided in addition to the compound main ram as described above.

It will be understood that I desire to comprehend within this invention such modifications as come within the scope of the claims and the invention.

Having thus fully described my invention, what I claim as new and desire to secure by Letters Patent, is:

1. In combination in a hydraulic press, a main cylinder, a partition member therein dividing said main cylinder into outer and inner chambers, a main plunger in said main cylinder having outer and inner portions disposed respectively in said outer and inner chambers and forming outer and inner piston areas therein, a platen connected to said main plunger, a surge tank immediately adjacent said cylinder with a port opening into said outer chamber and another port opening into said inner chamber, a surge valve in each port adapted automatically to open to admit fluid from said surge tank into each of said chambers in response to the idle advance of said main plunger whereby to prefill both of said chambers automatically during said idle advance, means for returning said main plunger to its retracted position, means responsive to the operation of said plunger-returning means during the return stroke of said main plunger for forcibly opening both of said surge valves to release fluid from both of said chambers through said ports directly back into said surge tank, and means for directing pressure fluid selectively to said inner and outer chambers of said main cylinder.

2. In combination in a hydraulic press, a main cylinder, a partition member therein dividing said main cylinder into outer and inner chambers, a main plunger in said main cylinder having outer and inner portions disposed respectively in said outer and inner chambers and forming outer and inner piston areas therein, a platen connected to said main plunger, a surge tank immediately adjacent said cylinder with a plurality of ports disposed on diametrically opposite sides of said partition member opening into said outer chamber and another port opening into said inner chamber, a surge valve in each port adapted automatically to open to admit fluid from said surge tank into each of said chambers in response to the idle advance of said main plunger whereby to prefill both of said chambers automatically during said idle advance, means for returning said main plunger to its retracted position, means responsive to the operation of said plunger-returning means during the return stroke of said main plunger for forcibly opening said surge valves to release fluid from both of said chambers through said ports directly back into said surge tank, and means for directing pressure fluid selectively to said inner and outer chambers of said main cylinder.

HOWARD F. MACMILLIN.
